UNITED STATES PATENT OFFICE.

ALBERT NÜRNBERG, OF BERLIN, GERMANY.

LAMP AND BURNER FOR LIGHTING PURPOSES.

SPECIFICATION forming part of Letters Patent No. 778,993, dated January 3, 1905.

Application filed June 2, 1904. Serial No. 210,915.

To all whom it may concern:

Be it known that I, ALBERT NÜRNBERG, a subject of the German Emperor, residing in Berlin, in the Empire of Germany, have invented certain new and useful Improvements in or Relating to Lamps and Burners for Lighting Purposes, of which the following is a specification.

The present invention relates to an improved lamp or burner in which lighting-gas or some other combustible gas—such as vapor of petroleum or alcohol, generator-gas, and the like—is used in combination with a supply of oxygen.

15 The figure shows a lamp according to this invention diagrammatically in vertical section, no further drawing being given in view of the simplicity of the invention.

20 *a* is the supply-pipe for the combustible gas, and *b* the supply-pipe for the oxygen. Lighting gas or vapor is admitted under any desired pressure through the pipe *a* to the annular chamber *c*, formed between an outer burner-pipe *d* and an inner burner-pipe *e*. Through 25 the pipe *b* oxygen is admitted into the inner pipe *e* by means of a nozzle *f*, which is connected to the oxygen-pipe *b*. The inner oxygen-pipe *e* projects downward beyond the outer pipe *d* and is closed at the bottom *g* and 30 provided with lateral openings *h*. The arrangement of the nozzle *f* and of orifices *h* in the oxygen-pipe *e* imparts to the burner the characteristic features of a Bunsen burner. When oxygen enters through the nozzle *f* 35 into the pipe *e*, the speed with which the oxygen escapes produces suction, so that atmospheric air is drawn through the openings *h*, said air mixing in the pipe *e* with the oxygen, the mixture meeting at the top of the burner at 40 *i* the combustible gas, a blue flame *k* being formed which renders the mantle *l*, suspended over the burner, strongly incandescent.

The mantle is suspended from a holder consisting of a wire handle *m* and a wire bracket 45 *n*, provided with a central eye or bent part *o*, from which the mantle is suspended. This mantle-holder is placed in recesses *p* in a ring

q, adjustably mounted on the parallel supply-pipes *a* and *b* by means of perforated lugs *r*, provided with set-screws *s*, so that the ring *q*, 50 and therefore the mantle-holder and the mantle, can be fixed at any desired level above the burner.

The pipes *a* and *b*, arranged symmetrically on both ends of the burner, are brought together above the burner at *t* and join at any desired point their main supply-pipes. The burner and the tubes connected to it are surrounded by a globe *u*, which can be moved up or down by means of suspending chains or 55 cords *v*. The chains pass over rollers *w* of a roller-carrier *x* and are secured to a central balance-weight *y*. As may be seen from the drawing, the two pipes *a* and *b* pass centrally through the roller-carrier *x* and the balance-weight *y*. The roller-carrier is secured to these pipes, while the balance-weight freely slides on them up and down, and thus does not present any obstacle to the movement of the globe, so that the burner can be very easily manipulated. 60 65 70 75

What I claim as my invention, and desire to secure by Letters Patent, is—

1. A lamp comprising an inner burner-tube, a concentric outer burner-tube, an oxygen-inlet nozzle to the inner burner-tube, said tube being provided with air-inlets below said nozzle and a combustible-gas inlet communicating with the outer burner-tube. 75

2. A lamp comprising an inner burner-tube, 80 a concentric outer burner-tube, an oxygen-inlet nozzle to the inner burner-tube, said tube being provided with air-inlets below said nozzle, a combustible-gas inlet communicating with the outer burner-tube and parallel vertical oxygen and combustible-gas supply pipes and inwardly-bent upper portions thereof. 85

3. A lamp comprising an inner burner, a concentric burner-tube, an oxygen-inlet nozzle to the inner tube, said inner burner-tube 90 being provided with air-inlets, and a combustible-gas inlet communicating with the outer burner-tube.

4. A lamp comprising an inner burner

member, an outer burner member, an oxygen-inlet nozzle to one member, one of said members being provided with air-inlets, a combustible-gas inlet communicating with the 5 outer member, and parallel vertical oxygen and combustible-gas supply pipes and inwardly-bent upper portions thereof.

In testimony whereof I affix my signature in presence of two witnesses.

ALBERT NÜRNBERG.
